UNITED STATES PATENT OFFICE.

WEBSTER GILLETT, OF FLUSHING, NEW YORK, ASSIGNOR TO THE ATLANTIC AND PACIFIC TELEPHONE COMPANY, OF SACO, MAINE.

TELEPHONE.

SPECIFICATION forming part of Letters Patent No. 296,829, dated April 15, 1884.

Application filed October 15, 1883. (No model.)

To all whom it may concern:

Be it known that I, WEBSTER GILLETT, of Flushing, Queens county, in the State of New York, have invented certain new and useful 5 Improvements relating to Telephones, of which the following is a specification.

This invention relates to telephones or apparatus for reproducing articulate sounds at distant points by the aid of electricity. I employ a series of independent telephonic transmitting devices operated by one and the same action of the voice, and all contributing to the effect produced at the other end of the line. I will show four sets of these parts; but it must 15 be understood that I am not confined to four. I can use a larger number. A less number—as three—may serve with some success. I mount a series of pairs of electrodes near each other, and in contact with a rigid piece receiving motion from a diaphragm. The rigid piece may be a concave disk firmly fixed by its center to the center of the ordinary vibrating diaphragm. It communicates the motion of that point to a series of pins, which, delicately 20 mounted and adjusted, each serve as one of the electrodes. Insulate the arms on which these are mounted, and make independent connections from each arm to its proper induction-coil. I control the series of local batteries, 25 each operating its proper induction-coil, by a single switch operating a single wire properly connected to the whole. I make one ground-wire, with suitable connections, serve for the whole series of induction-wires, each receiving 30 its proper current from an independent induction-coil.

The following is a description of what I consider the best means of carrying out the invention.

40 The accompanying drawings form a part of this specification.

Figure 1 is an elevation of the transmitter, showing the interior or back face. Fig. 2 is a section on the line xx in Fig. 1. This shows 45 one of the adjustable cylinders and adjacent parts in elevation. Fig. 3 is a section through the cylinder and immediately adjacent parts, on a larger scale. Fig. 4 is a section on the line yy in Fig. 1, on the same scale as Fig. 3.

Fig. 5 is a diagram of the instruments with 50 their connecting-wires, batteries, and ground-connections.

Similar letters of reference indicate corresponding parts in all the figures where they occur.

55 In the transmitter, Figs. 1 to 4, A' is a mouth-piece fitted in a board, A , in rear of which is mounted a diaphragm, B , firmly clamped by a ring, D^3 . To the middle of the diaphragm B is connected a concave disk, B' , firmly secured to the diaphragm by a screw, B^2 . The disk B' partakes of all the movements of the center of the diaphragm. To the ring D^3 are rigidly secured by screws D' four arms, D , each separated from the ring D^3 by insulators 60 D^2 , of hard rubber or other non-conducting substance. A wire, d , makes an electrical connection between each arm D and the negative pole of a battery, L . The arms D extend inward until they nearly touch each other. The 65 inner end of each is screw-threaded to match the screw-threaded exterior of a cylinder, G , inserted therein, which is provided with an enlarged head or wheel, G' , in which are bored holes adapted to receive a lever, (not represented,) by which it can be turned to adjust it with any degree of nicety in its bearings in the arm D . The interior of each cylinder G is equipped with two disks of soft vulcanized rubber or analogous material, $I I'$, between which is 70 imprisoned a quantity of granulated gas-carbon, J , or other substance of high resistance, having preferably a fineness about equal to ordinary rifle-powder. The disk I' is tight. The disk I is perforated in the line of its axis, 75 and receives a pin, E , having an enlargement or head, which, when the pin is pressed home, bears firmly against the outer face of the disk I , with the other end of the pin extending a little distance into the powder J . The disk I 80 is firmly pressed home in the cylinder by means of an internally-flanged and threaded thimble, G^2 . A conducting-wire, e , connects the head of each pin E with the positive pole of the same battery, which connects, by the 85 wire d , to the arm D . It follows that there is a circuit from the battery through the wires d 90 e , which is obstructed by its difficult passage 95

from the pin E through the granulated carbon J to the interior of the cylinder G. The force of this current will vary with every fluctuation in the conductivity. A variable pressure exerted on the head of the pin E will induce a fluctuation in the force of the current, for two reasons: The pin E will be thrust farther in and withdrawn, thus increasing and diminishing the amount of surfaces in contact between the pin E and the powder J. This is one means by which the conductivity is varied. Furthermore, the shoulder formed by the head of the pin E rests fairly against the outer face of the soft-rubber disk I, and every variation in the pressure on the pin will be transmitted through the disk and felt by the powder J. Each variation in the pressure on the powder changes its conductivity. This is the second means by which the conductivity is varied. These two fluctuations operate always in the same direction to re-enforce each other. An increased pressure on the head of the pin E results in both an increased pressure on the powder J, and also in a thrusting of the pin E deeper into the powder, and a diminution of pressure on the head of the pin E results in a diminution of pressure on the powder J and the partial withdrawal of the pin E from the powder, so as to diminish the surfaces in contact. The parts are so proportioned that the heads of the pins E are presented near the periphery of the concave disk B'. In adjusting the apparatus the cylinders G are turned around, so that by the engagement of their screw-threaded surfaces in the arms D they are set so that the head of each pin E makes the delicate contact with the disk B', sometimes known as "telephonic contact." When a word is spoken into the mouth-piece A' and vibrates the diaphragm B, the vibrations of the center of the diaphragm are communicated through the concave disk B' equally to all the pins E, and, by the two means described, induce fluctuations in the force of the current through each of the four sets of wires d e:

An induction-spool, F, is included in each circuit. The induction-coils may be of the ordinary construction, a coarse insulated wire being wound around a core of soft-iron wires carrying the primary current from the connected battery L, while a fine insulated wire wound exterior thereto is ready to transmit, through suitable connections, the secondary current, which is produced in this closely-associated fine wire by what is known as "induction," at each fluctuation in the force of the primary current. To the two ends of the induction-coil, which is wound in the usual way on the induction-spool F, are connected two conducting-wires, f h. Either of these wires f h may, by connecting one with the earth and the other with the line M, serve to transmit its current over the line and induce vibrations at the other end. All four sets communicate simultaneously the same signals. I arrange for combining them and sending the

united effect of the four over the same line-wire.

F' is the ground-plate at the transmitting end of the line. f' is a single wire leading therefrom to the vicinity of the instrument, where it is connected by switch-plugs C with the several wires f leading to the four induction-spoils F. K is the ground-plate at the opposite end of the line. k is a single wire, 75 connecting from K, through the receiving-instrument and through the line M, to the vicinity of the transmitting-instrument, where it is connected to each of the four wires h leading back to the induction-coils in the respective induction-spoils F. A connection very similar to this is made with the primary currents. The primary currents, through the batteries L and their respective wires d e, pass at one point through a single wire, e', so that 80 a single switch-plug, C', may connect and disconnect the whole at once. The arrangement to effect this is indicated in Fig. 6, where the four wires e leading from the four primary coils in the spools F are united by a short 85 cross-wire, e', to a single wire, e'', which connects through the switch-plug C' to a longer single wire, e'', which in its turn is connected to four short wires, e', leading to the positive poles of the several batteries L. The batteries are all connected to the induction-coils in the same manner and direction, and the induction-coils are all wound in the same direction relatively to each other.

Having thus described my invention and in what manner the same is to be performed, I claim as my invention the following improvements in telephones—

1. In a telephone, the combination of a series of separate pins, E, connected with the carbon powder J to form a variable-resistance device, and the concave disk B', fixed to a point in the vibrating disk B, whereby simultaneous vibration may be communicated to said pins, substantially as set forth.

2. In combination with the variable-resistance device formed by the pins E and carbon powder J, and the arms D, carrying the variable-resistance devices, the electrical connections d e, the disk B', and the diaphragm B, substantially as and for the purposes specified.

3. In a telephone, the cylinders G, carrying carbon powder J and engaging screw-threads in the arms D, the pins E; and the disks B and B', the parts J and E forming a variable-resistance device, which may be regulated by turning the cylinder G, substantially as specified.

In testimony whereof I have hereunto set my hand, at New York city, New York, this 20th day of September, 1883, in the presence of two subscribing witnesses.

WEBSTER GILLETT.
